UNITED STATES PATENT OFFICE

FREDERICK W. JACKSON, OF NEEDLES, CALIFORNIA

PLUG RETAINER

Application filed December 27, 1928. Serial No. 328,789.

This invention relates to a device adapted to be associated with a tubular body for holding a plug or like closure against accidental displacement within the tubular body and the general object is to provide an improvement upon the construction illustrated in my patent granted on March 25, 1924, No. 1,488,393 and to provide a construction which is simpler to manufacture, cheaper in cost and equally effective as a means for holding the plug in place.

My invention is illustrated in the accompanying drawing, wherein:

Figure 1 is a face view of a tubular body for holding a plug, with my plug retaining device thereon;

Figure 2 is a like view to Figure 1 but showing the retaining device turned in its inoperative position;

Figure 3 is a section on the line 3—3 of Figure 1;

Figure 4 is a section on the line 4—4 of Figure 1.

Referring to the drawing, 10 designates a tubular member and 11 a plug having screw-threaded engagement therewith, the extremity of the plug being formed with a socket 12 whereby a socket wrench may be applied to remove the plug from its engagement with the tubular member.

The tubular member is illustrated as being reduced at one end and exteriorly screw-threaded at 13 but I do not, of course, wish to be limited to this.

The tubular member is formed with a lateral projection 14 which is channeled upon its outer face to provide opposed walls 15. This protuberant portion or lug 14 is vertically bored at 16. The walls 15 upon their upper surfaces are rounded. Extending through the bore 16 is a shank 17 having at its upper end a head 18. The lower end of the shank 17 is screw-threaded for the reception of a nut 19 and disposed between this nut and the under face of the lug 14 is a compression spring 20. The head 18 is of such length that when the head is turned into alinement with the channel formed between the walls 15, the free end of the head will project over the plug 11 and, therefore, pre-

vents the plug from being rotated or unscrewed or otherwise removed from the tubular member 10. The spring 20 acts to hold the head 18 firmly down between the walls 15 and over the plug.

When the head is pulled outward or the shank forced outward so that the head clears the walls 15, the head may be rotated to a position at right angles to the walls 15 and rest upon the outer faces thereof and under these circumstances the plug will be free to be unscrewed. The tension of the spring 20 causes the head to bear firmly against the outer faces of the walls 15 but if the head be rotated beyond a certain point the inwardly inclined or rounded faces of the walls 15 will cause the head to snap into place. It will be seen that the head may be turned from its inoperative position in either direction toward its operative position and it will snap into place and lock the plug from withdrawal.

The nut 19 is preferably held in place upon the shank 17 by means of a cotter pin or other key. It will be seen that this construction is very simple, is thoroughly effective, that it may be much more cheaply made than the construction illustrated in my prior patent and that the head cannot be accidentally turned away from its locking position unless the head be forcibly shifted beyond the outer faces of the walls 15.

It will be likewise seen that these angled faces cause the head to wedge upward or outward as it is turned at right angles to the walls and thus place a final tension upon the spring which will hold the head firmly in its inoperative position.

I claim:

1. In a device of the character described, a tubular member, a plug engaged therewith and means for retaining the plug against accidental displacement comprising a lug projecting from the tubular member and having a wall extending substantially radially with reference to the plug, the stem extending through said lug and carrying a head at its outer end, a spring urging the stem in a direction to carry the head toward the lug, the head being rotatable into a position parallel with the wall of the lug or

at right angles thereto when the head and the stem are lifted against the action of the spring, the outer face of said wall being inclined from its middle in opposite directions.

- 5 2. A device of the character described, comprising a tubular member, a plug therefor and means for retaining the plug against accidental displacement comprising a lug projecting from the tubular member and having a radial groove upon its outer face, a head having a stem extending through the lug, a spring urging the stem inward and the head against the outer faces of the grooved walls.
- 10 3. In a device of the character described, a tubular member, a plug therefor and means for retaining the plug against accidental displacement comprising a lug projecting from the tubular member and having a radial groove upon its outer face, a head having a stem extending through the lug, a spring urging the stem inward and the head against the outer faces of the grooved walls, the walls of said groove having their outer faces
- 15 inclined toward the plane of the edge face of the tubular member from a middle point in opposite directions.
- 20
- 25

In testimony whereof I hereunto affix my signature.

30 FREDERICK W. JACKSON.
